UNITED STATES PATENT OFFICE

120,010

DESIGN FOR A RING OR SIMILAR ARTICLE

William Merle Itton, Chicago, Ill.

Application February 19, 1940, Serial No. 90,356

Term of patent 7 years

To all whom it may concern:

Be it known that I, William Merle Itton, a citizen of the United States, residing at Chicago, in the county of Cook and State of Illinois, have invented a new, original, and ornamental Design for a Ring or Similar Article, of which the following is a specification, reference being had to the accompanying drawing, forming part thereof.

Fig. 1 is an enlarged perspective view of a ring or similar article showing my new design.

Fig. 2 is a view taken on line 2—2 of Fig. 1.

I claim:

The ornamental design for a ring or similar article, as shown.

WILLIAM MERLE ITTON.
